UNITED STATES PATENT OFFICE

101,083

DESIGN FOR A COMBINATION RANGE AND AIR CIRCULATING HEATER

Joseph E. Leonard, Berkeley, Calif., assignor to
Hammer-Bray Company, Ltd., Oakland, Calif.,
a corporation of Nevada

Application September 26, 1935, Serial No. 58,718

Term of patent 14 years

To all whom it may concern:

Be it known that I, Joseph E. Leonard, a citizen of the United States, and a resident of Berkeley, county of Alameda, and State of California, have invented a new, original, and ornamental Design for a Combination Range and Air Circulating Heater, of which the following is a specification, reference being had to the accompanying drawing, forming part thereof.

The figure is a perspective view of a combination range and air circulating heater showing my new design.

The dominant feature of the design resides in the portions shown in full lines.

A characteristic feature of my design resides in the arrangement and appearance of the grill in the end wall of the article. The other end of the article, not shown, is substantially plain.

I claim:

The ornamental design for a combination range and air circulating heater substantially as shown and described.

JOSEPH E. LEONARD.
